UNITED STATES PATENT OFFICE.

GEORGE W. NELSON, OF CLEVELAND, OHIO, ASSIGNOR TO THE STANDARD SEWING MACHINE COMPANY, OF CLEVELAND, OHIO, A CORPORATION OF OHIO.

SEWING-MACHINE.

1,252,931.

Specification of Letters Patent.

Patented Jan. 8, 1918.

Application filed May 21, 1912. Serial No. 696,890.

To all whom it may concern:

Be it known that I, GEORGE W. NELSON, citizen of the United States, and resident of Cleveland, in the county of Cuyahoga and State of Ohio, have invented certain new and useful Improvements in Sewing-Machines, of which the following is a specification.

This invention relates to sewing machines, and particularly to that class of sewing machines in which successive groups or series of stitches are made at separated points in the work, as for example, in button sewing machines, etc.

While certain features of the present invention are applicable to sewing machines of various types the main features of the invention are especially adapted to machines of the class just mentioned for forming series or groups of stitches at separated points in the work, and particularly to machines of this class in which a single thread is used, that is to say, in button sewing and similar machines for forming groups of chain-stitches. In chain-stitch machines of this class it is customary to sever the thread on the completion of a group or series of stitches by a suitable means under the control of the operator. It has been found that in such chain-stitch machines provision preferably should be made for certain necessary manipulation of the thread, to wit: that means be employed for pulling off from the source of supply a sufficient length of thread to permit the forming of the first stitch of a series without drawing down the end of the thread below the upper surface of the work, that the length of the thread beyond the needle eye at the beginning of the making of such a series of stitches should be determined in order that there may be no excess thread beyond what is necessary for the formation of the first stitch, and that on the completion of a series or group of such stitches the end of the thread remaining in the material operated upon should be tied or knotted in order to prevent raveling out of the stitches.

In a prior application of mine, Serial No. 681,208, filed March 2, 1912, there is disclosed a machine of this same type so far as the structure and general organization of its parts are concerned, and in which means are provided for controlling with precision the amount of thread drawn off

from the supply for the first stitch of a series or group, and for also regulating the length of the end of thread extending beyond the eye of the needle, for the purpose of avoiding the use of an excessive amount of thread in making the first stitch or loop of each new series. In the machine of said application a thread-restraining device or thread-clamp is associated with suitable pull-off means and with a work-holder in such a manner that on the completion of a series of stitches, and before the severing of the thread, a sufficient length of thread may be drawn off from the source of supply to permit the proper formation of the first stitch of the next series, after which the thread is broken and the severed end of the thread is drawn back until the portion beyond the eye of the needle is substantially just sufficient to permit the first stitch of the new series to be properly formed. In said application, however, the thread-restraining device or thread-clamp, and the pull-off means, which included as one of its functions the drawing back of the severed end of the thread, were associated and connected with the work-holder for actuation by the operator after the automatic stopping of the machine at the end of a series of stitches.

In the present machine the principal devices just referred to, to wit: a thread-restraining device for clamping the thread at a suitable time after the completion of a series of stitches, and pull-off means for drawing off from the source of supply a sufficient length of thread for the first loop of a new series, and for also drawing back toward the source of supply the end of the severed thread, are or may be retained; but the principal feature which distinguishes this invention from that of said prior application, and in general from other machines of the prior art, is the employment of means for automatically performing each of these functions of clamping the thread and pulling off the thread in one direction or the other after one series of stitches has been completed and the action of the needle-bar mechanism is substantially finished and before the next series is started. In other words, the present machine is distinguished from that of said prior application mainly by reason of the fact that automatic instead of manual means is employed for performing certain functions which were formerly

manually related to the operation of severing the thread, but which in the present machine are manually unrelated to the thread-severing function, and are separated therefrom and performed wholly automatically without reference to when the severing operation may take place.

Another feature of the invention relates to the timing of these various automatically controlled operations just referred to. The thread-restraining device of the aforesaid application was timed to come into action to clamp the thread after the drawing off from the source of supply of sufficient thread for the formation of the first loop of a new series. In the present case, however, this thread-restraining device is timed to permit a pull-off device to draw off this amount of thread from the supply after the thread has been clamped, and to pull off the thread from a point in the rear of that at which the thread is clamped, instead of from a point in advance of the thread clamping device as was the case in said prior application. Furthermore, the thread-clamp of the present machine preferably engages and holds the thread at a point on the face-plate of the machine and at a comparatively short distance from the needle, so that but a short length of thread is located between the two points at which the thread is substantially fixed just before it is severed.

Other features of the invention not hereinbefore referred to will be hereinafter described and claimed and are illustrated in the accompanying drawings, in which—

Figure 1 is a side elevation of one specific type of sewing machine embodying the invention, to wit, a button-sewing machine, and shows the parts in the positions they occupy during the normal operation of the machine and prior to the automatic stopping thereof;

Fig. 2 is a similar view, showing the positions of the parts on the automatic stopping of the machine and the actuation of various thread-controlling devices hereinbefore referred to;

Fig. 3 is a front view of the machine, showing the parts in the same positions as in Fig. 2;

Fig. 4 is a plan of the machine, with the parts in the positions shown in Fig. 1;

Figs. 5 and 6 are details, illustrating in perspective the operative and inoperative positions respectively of the thread-clamp and an associated pull-off device hereinbefore referred to, and

Fig. 7 is a detail illustrating the construction and operation of one of the braking devices of the automatic stop mechanism.

Similar characters designate like parts in all the figures of the drawings.

While various features of the invention may be embodied in various specific types

of sewing machines, most of them are specially applicable to that class of sewing machines for forming groups of separated stitches, and particularly to button-sewing machines, for which reasons the various features of the invention are illustrated in the drawings as embodied in a button-sewing machine. Most of the parts of this machine are or may be similar to those of other button-sewing machines heretofore used, such as, for example, as the "Standard" button-sewing machine, and particularly to those of the specific type of "Standard" machine shown in the aforesaid application. In the construction illustrated the main frame comprises upper and lower portions, 2 and 3, suitably connected and containing suitable chambers, bearings, etc., for the various operating parts. The main driven member, for example, is shown as a fast disk, 4, associated with a loose pulley, 5, these being, as usual, in the form of hand-wheels to permit them to be readily manipulated. The disk 4 is carried by a suitable main shaft (not shown) having at its extreme forward end a looper, such as 7, of well-known chain-stitch type. Associated with the disk 4 and pulley 5 is some suitable means for starting and stopping the machine. 8 and 9 designate respectively the usual needle and needle-bar, the latter of which is intended to be operated from the main shaft substantially in the well-known manner. Suitable means are also employed for effecting the tensioning, taking-up and guiding of the thread in the normal operation of forming successive stitches, 11 and 12 indicating a pair of tension devices located on the top of the machine arm, the second being the usual automatic tension device, while 13 is a take-up device carried and operated by the needle-bar, and 14, 15, 16, 17 and 18 are a series of guides for properly directing the thread in its passage from the source of supply to the needle, all being of substantially the usual construction and operation as found in machines of this kind. In such machines there is also adjacent to the needle and looper a suitable work-holder or button-clamp, which is or may be substantially similar to those of prior machines, and particularly to that shown in the aforesaid application, this button-clamp being designated generally by H.

Referring first to Figs. 1 and 2, t indicates the needle-thread, which in this case is the single thread of a chain-stitch button-sewing machine. This thread is passed through the guides, tension devices, take-up device, etc., in the manner illustrated in the various views. As is well known, in all machines of this type a series or group of stitches is made, as for example, in sewing on a button, and the machine is then brought to a stop, usually by an automatic stop mechanism.

On the stopping of the machine the operator then usually has to perform one or more operations manually in order to complete the work being done at one point in the 5 length of the material operated upon, and then has to shift the work to a new position. Before considering in detail the manner in which the thread is to be acted upon on the stopping of the machine, the mechanism 10 preferably employed for bringing about the automatic stopping of the machine will be briefly described.

At the beginning of the operation of the machine on the work, and at the beginning 15 of the operation of making any new series or group of stitches in the work, as, for example, in sewing on a button, such as *b*, the mechanism for starting and stopping the machine will be in the position shown in 20 Fig. 1. The main element of this mechanism is, of course, the disk 4. In the present case, as in the aforesaid prior application, this disk is intended to be engaged at opposite sides thereof when the machine is to be 25 automatically stopped. Two braking surfaces are provided for this purpose, which surfaces are of course clear of the driven member 4 when the machine is in operation. They serve to clamp the disk 4 between them 30 at the proper moment, this action being preferably controlled by a strong spring for applying them substantially instantaneously to opposite sides of the disk 4 when the machine is to be stopped. Here the disk 4 and 35 pulley 5 are forced into engagement with each other by a suitable starting lever, 19, having in line with the center of the pulley 5 a cone-pointed pin, 20, holding the two pulleys firmly together during the time that 40 the operator desires the machine to be running. Another lever, such as 21, of substantially ring form, surrounds the disk 4 and pulley 5 and is substantially parallel with the lever 19. These two levers are pivoted 45 at their lower ends to the lower frame portion 3 of the machine. At its upper end the starting lever 19 has a forwardly and downwardly extending or overhanging arm, 22, the inner face of the depending portion of 50 which carries a suitable braking device, 23, in juxtaposition with the forward side of the disk 4. The ring-shaped lever 21 has near its upper side a corresponding braking device, 24. The two levers 19 and 21 and the 55 braking devices or pads carried thereby are intended to be moved together in opposite directions, the main portions moving away from each other to apply the brake and toward each other when the brake is removed 60 and the pulleys coupled together. Any suitable means may be employed for operating said levers in this manner, provided it is such as to effect a quick and powerful application of the brake. Here a toggle connection 65 is combined with a strong spring, 25,

the spring serving to apply the braking devices quickly to the disk 4 while the toggle serves to obtain a powerful grip through said braking devices upon opposite sides of said disk. The toggle connection shown 70 comprises links, 26 and 27, connected respectively to the starting lever 19 and to a fixed point on the upper frame member 2. At their point of connection these links are also pivoted to a third link, 28, the upper end of 75 which is pivoted to a rock-arm, 29, on a rock-shaft, 30, journaled in lugs at the upper rear end of the main frame 2. This rock-shaft also has secured to its front end two rock-arms, 31 and 32, and at its rear end a 80 rocking pawl, 33. The rock-arm 31 is intended to be operated by connections from a treadle or other suitable part to start the machine, while the pawl 33 constitutes one 85 element of a holding device or detent adapted to be engaged by a complementary element, such as the hooked upper end 34, of a long lever, 35, pivoted near its center on a suitable fixed part of the frame and having its lower end faced or beveled, as indicated 90 at 36, to coöperate with tripping means for bringing about the automatic stopping of the machine. The rock-arm 32 is connected by means of a rod, 37, to the free end of a rock-arm 38 secured to one end of a rock- 95 shaft, 38, journaled in bearings at the rear end of the machine and carrying eccentrics 38" for operating a pair of substantially horizontal links, 39, the rear ends of which are connected to the ring-shaped lever 21 100 near the upper end thereof. The construction and organization of these parts are such that when the starting lever is moved rearwardly or in a direction to release the driving pulley from the driven disk the toggle is 105 straightened and at the same time the links 39 are moved forward slightly, their movement being small as compared with the rearward movement of the starting lever, and the two braking devices 23 and 24 are 110 brought instantaneously and with powerful combined spring and toggle action into braking engagement with opposite sides of the disk 4 to stop the machine. The machine is intended to be stopped each time 115 with all of the parts in a predetermined position, to wit, with the take-up 13 in a raised position and the needle at or about the limit of its up stroke, in readiness for the taking of the first stitch of the next succeeding series. 120 The means used is a wedge, such as 4', on the disk 4 for increasing the friction opposed to the rotation of the parts at a predetermined point. It coöperates with the braking devices 23 and 24 to wedge the disk between 125 the braking surfaces and bring the machine quickly, but with a properly graduated action, to a stop at the exact point desired. To start the machine the operator presses a treadle or other device and through 130

connections to the rock-arm 31 the pawl 33 is drawn down until it passes below the hook 34 of the lever 35, when it is engaged by said hook, as shown in Fig. 1, said hook 5 being normally forced toward said pawl, as by means of a spring 40. This movement of the rock-arm 31, etc., serves to strike the toggle and withdraw the braking devices from the opposite faces of the disk 4, and in 10 these positions the parts are held as just described until the lever 35 is tripped automatically on the completion of a predetermined series or group of stitches.

Any suitable means may be employed for 15 tripping this lever. Preferably the tripping means is operated from the main shaft (not shown) through a cross-shaft 41, driven from said main shaft by gearing (not shown) by means of which a relatively slow 20 rotary movement is imparted to this cross-shaft. On the completion of the predetermined group of stitches the cross-shaft is intended to bring into operation a releasing device. This releasing device is shown 25 as carried by a disk, 42, and is in the form of a radial pin, 43, slideable in and out of operative position and suitably held in place. When projected into the position shown in Fig. 1 the pin serves to trip the 30 lever 35 automatically once at each rotation of the disk. When not projected the machine may be used for straight-away stitching. When the pin 43 reaches the position shown in Fig. 2 it rides over one of the 35 beveled faces at the end 36 of the lever 35 and rocks said lever, releasing it from the pawl 33, whereupon the spring 25 will immediately bring about the automatic stopping of the machine as previously described.

40 The parts just specifically described are, as before stated, substantially those of previous machines of this general class and particularly of the machine shown in the aforesaid application. From any suitable part of 45 the mechanism so described the automatic control of the thread-clamping and pull-off devices before referred to may be effected. In this construction, however, the automatic stop mechanism of said prior machine is utilized for this purpose. In order that it may be so used the shaft 30 is illustrated as having in addition to the parts previously mentioned, a cam, 44, movable from the position shown in Fig. 1 to that illustrated in Fig. 2 50 for the purpose of actuating connections between said cam and the thread-clamp, pull-off devices, etc. The connections employed may be any suitable for the purpose, provided that the timing of the operation of the 55 parts actuated thereby is that which is herein described. The specific connections shown comprise a lever, 45, secured to a fixture at the upper rear end of the frame of the machine and the lower end of which co-operates 60 directly with the cam 44 while the upper end

is in position for engaging and actuating a controlling member, such as a rod 46, mounted to slide in guide-ways preferably at the upper side of the machine and extending from the front to the rear thereof. Various 70 guides for said rod are indicated at 47, 48 and 49. A stop is shown at 50 for limiting the rearward movement of this rod, the forward movement being determined by the throw of the lever 45. In this construction 75 the rod 46 constitutes the immediate actuator for various elements in which the main features of the present invention are embodied. One of these is a suitable thread-clamp for clamping the thread automatically 80 on the completion of a predetermined group of stitches and the consequent stopping of the feed movement of the thread, while another is a pull-off device for automatically pulling off from the source of 85 supply a suitable length of thread for the first stitch of a new series, and two others shown are a device for automatically releasing the automatic tension device of the machine and a pull-off device in the form 90 of a check-spring for automatically drawing up through the eye of the needle the long depending severed end of the thread after said thread has been properly clamped and severed. 95

In the machine shown in the aforesaid application the thread-clamp and pull-off devices were manually actuated by the operator in predetermined timing and the thread was severed after such manual clamping of 100 the thread following the completion of a group of stitches and the knotting of the thread. In the present machine these devices are not operated manually but automatically in predetermined timing, and the functions 105 of clamping the thread and pulling off thread for the first stitch of a new series are entirely separated from the function of manually severing the thread, which severing operation may take place at any time after the clamping and pulling off operations have been finished.

The thread-restraining device or thread-clamp for clamping the thread on the completion of the predetermined group of stitches may be of any suitable type, but is here shown as comprising fixed and movable clamping jaws, 52 and 53, the former of which is fixed to the front plate of the machine, while the latter is illustrated as forming part of an angle lever, 54, pivoted in a notch of a stud, 55, on said front plate by means of a pin, 56. (See Figs. 5 and 6.) At its upper end this angle lever has an opening in which the actuating rod 46 works, the movement of this lever being controlled by said rod and by a spring, 57, thereon working between the upper end of the lever which is normally stopped against a head, 58, at the forward end of said rod

and a suitable fixed stop. In the normal position, shown in Figs. 1 and 6, this thread-restraining device or thread-clamp is open and the rod is in its retracted position.

- 5 When the detent 33 is released, however, said rod is shifted quickly forward to the position shown in Figs. 2 and 5 in which the spring 57, which actuates it to that position, holds the movable member of the thread-restraining device against the fixed member 52 and clamps the thread in place between them. The thread is, of course, released by the return of the rod to its normal position, that is, by the resetting of the parts.

The rod 46 also carries in this case means for operating a pull-off device for pulling off sufficient thread for the first stitch of a new group or series. This pull-off device 20 also may be any suitable for the purpose. It is illustrated at 59 as an angle lever movable in a substantially horizontal plane and having a vertical finger, 60, for engaging the thread and pulling it aside from 25 its normal position to the dotted line position indicated in Fig. 4 to pull off the necessary length of thread. The short arm of this lever is shown as bent and pierced for the reception of the adjacent portion of the 30 rod 46, a spring for normally holding this pull-off device in the full-line position shown in Fig. 4, being illustrated at 61. As shown, this spring is normally extended to hold the pull-off device in the position indicated by full lines in Fig. 4. When the 35 pawl 33 is tripped, however, said spring is put under compression between a fixed stop face on the head of the machine and a stop face on the rod 46. The stop on the 40 rod is preferably adjustable and is illustrated at 62 in conjunction with means, such as 63, for locking it in any desired adjusted position for regulating the length of throw of the pull-off device and thereby the length 45 of thread drawn off from the spool or thread-supply. It will be obvious that the spring 61 will be released and, expanding, will restore the pull-off device to its normal position when the parts are reset for 50 a new series of stitches, as shown in Fig. 1.

The automatic tension device 12 at the moment the pull-off device 59 is operated to draw from the supply a length of thread sufficient for a stitch should, of course, be open. This opening may take place in the 55 normal operation of said automatic tension device or separate means may be employed for opening this tension device at such time. In the present case the rod 46 60 is shown as having thereon a releasing device, 64, in the form of a finger movable into position between the disks of the automatic tension device 12 for the purpose of releasing the tension. Normally this device 65 is retracted to a position in which it exer-

cises no control over the automatic tension device, it being held in this normal position, as, for example, by means of a suitable spring, 65, between a cheek of the combined guide and bearing 48 and one face of the releasing device itself. Normally this spring is extended as shown in Fig. 1, but when the machine is stopped by the tripping of the detent 33 it is put under compression as 70 illustrated in Fig. 2.

In addition to the thread-clamp, the main pull-off device, and the release for the automatic tension device just described, the controlling rod 46 also preferably governs the operation of another pull-off or take-up device, in the form of a check-spring, for pulling back the thread *t* through the eye of the needle a predetermined distance after the same has been severed at the work. The device employed for this purpose is shown 80 in detail at 66 in Figs. 5 and 6, from which it will be seen that it will operate during the regular operation of the machine to perform the usual function of a check spring, that is, controlling or taking up slack thread 85 during the descent of the needle, and also serves, on the severing of the thread at the work, to perform the additional function of pulling back the severed end of the thread 90 through the eye of the needle until only a sufficient length of thread is left beyond 95 said eye to permit the proper formation of the first stitch of a new series.

From the foregoing description of the thread-clamp, the pull-off devices, and the release for the automatic tension device, it will be seen that the rod 46 exercises, through the action of a suitable part of the mechanism of the machine, which in this instance is the stop motion, an automatic 100 control over the action of all of these parts which are therefore caused to operate in a predetermined timing. The timing in this case is such that on the completion of the predetermined series or group of stitches, 105 and when the action of the needle-bar mechanism is substantially finished, the thread is first clamped by the thread-restraining device 52—53, the automatic tension 110 12 is then released, the pull-off device 59 between this tension device and the thread-clamp is actuated to the position shown in dotted lines in Fig. 4 to draw off from the source of supply a suitable length of thread, and the second pull-off device, or check-spring, is 115 brought into position and put under tension (see Fig. 2) so that it will be in condition for pulling up the loose end of the thread on the severing of the same.

The severing of the thread may be performed substantially in the usual manner, that is to say, by a suitable manual or treadle connection to the usual operating lever, 67, connected to the button-clamp by a suitable connection 68. The raising of 125 130

the button clamp around the pivotal connection 69 as a center produces a strain on the thread which is held against feeding by the clamp 52, 53, and effects a breaking or severance of said thread close to the under side of the work.

What I claim is:—

1. A sewing machine, comprising means for forming a group of stitches said means including a needle, a work-holder, means for severing the thread, a thread-restraining device coöperating with said severing means located in position for clamping the thread at a point above said needle, and automatic means for rendering said thread-restraining device effective on the completion of said group of stitches and the stopping of the feed of the thread.

2. A sewing machine, comprising means for forming a group of stitches said means including a needle, a work-holder, means for severing the thread, a thread-restraining device coöperating with said severing means located in position for clamping the thread at a point above said needle, and automatic means governed by said stitch-forming means for rendering said thread-restraining device effective on the completion of said group of stitches and when the action of the needle-bar mechanism is substantially finished.

3. A sewing machine, comprising means for forming a group of stitches said means including a needle, a work-holder, means for severing the thread by the lifting of said work-holder, a normally ineffective thread-restraining device operable independently of said severing means located in position for clamping the thread at a point above said needle, and automatic means governed by said stitch-forming means for rendering said thread-restraining device effective on the completion of said group of stitches and when the action of the needle-bar mechanism is substantially finished.

4. A sewing machine, comprising means for forming a group of stitches, a work-holder, means for severing the thread, a thread-restraining device coöperating with said thread severing means, a pull-off device independent of said thread restraining device, and automatic means for rendering said thread-restraining and pull-off devices effective on the completion of said group of stitches.

5. A sewing machine, comprising means for forming a group of stitches, a work-holder, means for lifting said work-holder, a thread-restraining device to positively clamp the thread, a pull-off device between which and the work-holder said thread-restraining device is located, and automatic means for rendering said thread-restraining device effective on the completion of said group of stitches.

6. A sewing machine, comprising means for forming a group of stitches, a work-holder, means for lifting said work-holder, a thread-restraining device to positively clamp the thread, a pull-off device between which and the work-holder said thread-restraining device is located, and automatic means for rendering said thread-restraining and pull-off devices effective on the completion of said group of stitches.

7. A sewing machine, comprising means for forming successive groups of stitches said means including a needle, a work-holder, and means for automatically stopping the machine upon the completion of each group of stitches, in combination with a thread-restraining device to positively clamp the thread at a point above the needle, a pull-off device, and means for automatically rendering said thread-restraining and pull-off devices successively effective in the order named upon the completion of each group of stitches.

8. A sewing machine, comprising means for forming successive groups of stitches said means including a needle, a work-holder, and means for automatically stopping the machine upon the completion of each group of stitches, in combination with a thread-restraining device to positively clamp the thread at a point above the needle, a pull-off device between which and the work-holder said thread-restraining device is located, and means for automatically rendering said thread-restraining and pull-off devices successively effective in the order named upon the completion of each group of stitches.

9. A sewing machine, comprising means for forming successive groups of stitches said means including a needle, a work-holder, and means for automatically stopping the machine upon the completion of each group of stitches, in combination with a thread-restraining device to positively clamp the thread at a point above the needle, a pull-off device operatively connected with said thread-restraining device, and means for automatically rendering said thread-restraining and pull-off devices successively effective in the order named upon the completion of each group of stitches.

10. A sewing machine, comprising means for forming successive groups of stitches said means including a needle, a work-holder, and means for automatically stopping the machine upon the completion of each group of stitches, in combination with a thread-restraining device to positively clamp the thread at a point above the needle, a pull-off device connected with said thread-restraining device and between which pull-off device and the work-holder said thread-restraining device is located, and means for automatically rendering said

- thread-restraining and pull-off devices successively effective in the order named upon the completion of each group of stitches.
11. A sewing machine, comprising means for forming a group of stitches said means including a needle, means for automatically stopping the machine upon the completion of said group of stitches, means for severing the thread, and automatic means operative subsequent to the stopping of the machine and prior to the restarting of the same for pulling the severed end of the thread backward through the eye of the needle a predetermined distance.
15. 12. A single thread sewing machine, comprising means for forming a group of stitches said means including a needle, means for automatically stopping the machine on the completion of said group of stitches, means for severing the thread at the under side of the work, and automatic means operative subsequent to the stopping of the machine and prior to the restarting of the same for pulling the severed end of the thread 25 backward through the eye of the needle a predetermined distance.
13. A sewing machine, comprising means for forming a group of stitches said means including a needle, a work-holder, means for severing the thread, a thread-restraining device, a take-up device for pulling the severed end of the thread backward through the eye of the needle a predetermined distance, and means for automatically rendering said 35 thread-restraining and take-up devices successively effective in the order named on the completion of said group of stitches.
14. A sewing machine, comprising means for forming a group of stitches said means including a needle, a work-holder, means for severing the thread, a thread-restraining device, a spring take-up device for pulling the severed end of the thread backward through the eye of the needle a predetermined distance, and means for automatically rendering said thread-restraining and take-up devices successively effective in the order named on the completion of said group of stitches.
15. A sewing machine, comprising means for forming a group of stitches said means including a needle, a work-holder, means for severing the thread, a thread-restraining device, a pull-off device in the rear of said thread-restraining device, a take-up device 55 in front of said thread-restraining device for pulling the severed end of the thread backward through the eye of the needle a predetermined distance, and means for automatically rendering said thread-restraining, pull-off and take-up devices successively effective in the order named on the completion of said group of stitches.
16. A sewing machine, comprising means for forming a group of stitches and severing the thread on the completion of the stitches
- of said group, a thread-restraining device, and automatic means in the rear of the thread-restraining device and operative on the completion of said group for pulling off thread for a stitch while said thread-restraining device is in its effective position, and automatic means in front of said thread-restraining device for pulling back the severed end of said thread automatically while the thread-restraining device is in said position.
17. A sewing machine, comprising means for forming a group of stitches, an automatic tension device, a work-holder thread severing means, and automatic means independent of said thread severing means for clamping the thread at the end of a group of stitches and for pulling off thread in the rear of said clamping point while the automatic tension device is in its ineffective position.
18. A sewing machine, comprising means for forming a group of stitches, an automatic tension device, a work-holder thread severing means, a thread-clamp independent of said thread severing means located in advance of the automatic tension device, a pull-off device between said thread-clamp and the automatic tension device for pulling off thread in the rear of the thread-clamp when the automatic tension device is in its ineffective position, and automatic means for rendering said thread-clamping and pull-off devices successively effective in the order named on the completion of said group of stitches.
19. A sewing machine, comprising means for forming a group of stitches, an automatic tension device, a work-holder, a controlling rod, and means for automatically shifting said rod to its operative position on the completion of said group of stitches, in combination with the following instrumentalities governed by said movement of the controlling rod and successively effective in the order named viz.—a thread-clamp, independent of said tension device and a pull-off device in the rear of said thread-clamp.
20. A sewing machine, comprising means for forming a group of stitches, an automatic tension device, a work-holder, a controlling rod, and means for automatically shifting said rod to its operative position on the completion of said group of stitches, in combination with the following instrumentalities governed by said movement of said controlling rod and successively effective in the order named viz.—a thread-clamp, means for releasing said automatic tension device, and a pull-off device between said automatic tension device and thread-clamp.
21. A sewing machine, comprising means for forming a group of stitches, an automatic tension device, a work-holder, a controlling rod, and means for automatically

shifting said rod to its operative position on the completion of said group of stitches, in combination with the following instrumentalities governed by said movement of the controlling rod and successively effective in the order named viz.—a thread-clamp independent of said tension device, and a check-spring for pulling back the thread at the needle after the thread has been severed.

10 22. A single thread sewing machine, comprising means for forming a group of stitches said means including a needle, a work-holder, a thread-clamp to positively clamp the thread located adjacent to and above the 15 needle and substantially in vertical alignment with it, a pull-off device for pulling off thread in the rear of said thread-clamp, means for rendering said thread-clamp and pull-off device successively effective on the 20 completion of said group of stitches, and

means for raising the work-holder while the thread-clamp is in effective position to sever the thread at the under side of the work.

23. A sewing machine comprising stitch forming means, a thread tension, and a pair of complementary thread breaking devices both located above the work, mechanism for actuating the stitch forming means, connections between the actuating mechanism and one of said devices for actuating the latter, and connections for manually operating the other of said devices.

Signed at Cleveland, in the county of Cuyahoga, and State of Ohio, this 14th day of May A. D. 1912.

GEORGE W. NELSON.
